UNITED STATES PATENT OFFICE.

WILLIAM H. KREMER, OF CANTON, ILLINOIS.

DESIGN FOR A JAR-COVER.

SPECIFICATION forming part of Design No. 30,265, dated February 28, 1899.

Application filed January 30, 1899. Serial No. 703,909. Term of patent 7 years.

To all whom it may concern:

Be it known that I, WILLIAM H. KREMER, of Canton, in the county of Fulton and State of Illinois, have invented a certain new Design for Jar-Covers, of which the following is a specification, and the accompanying drawings are an illustration.

In the drawings, Figure 1 is a plan of the design. Fig. 2 is an elevation of the same, and Fig. 3 is a section on line *x* in Fig. 1.

The essential features of the design are a circular disk 1, having a central depression 2, a downward-extended annular rim or flange 3, and a pair of centrally-elevated ribs 4, par-

allel one with the other and describing chords 15 on the upper surface of the disk equidistant from the center thereof and outside the central depression.

What I claim is—

The design for a jar-cover substantially as 20 herein shown and described.

In testimony whereof I sign my name in the presence of two subscribing witnesses.

WILLIAM H. KREMER.

Witnesses:

BOLLIVER NEWTON,
THOMAS N. HORNETT.
